UNITED STATES PATENT OFFICE

GEORGE H. EMERSON, OF BALTIMORE, MARYLAND

FEED-WATER-HEATING SYSTEM FOR LOCOMOTIVES

Application filed June 26, 1926. Serial No. 118,680.

My invention relates to locomotives and it has particular relation to locomotive feed-water heaters.

One object of my invention is to provide a feed-water heater system, wherein the feed water may be raised to an extremely high temperature before being inserted into the boiler.

Another object of my invention is to provide a feed-water heating system, wherein exhaust steam may be caused to heat the feed water to a temperature at which degasification readily occurs in an open tank and also to heat further the degasified feed wa-
ter prior to insertion into the boiler.

Other objects and applications of my invention, as well as details of construction and operation, whereby my invention may be practiced, will appear more fully herein-
after, when taken in connection with the accompanying drawings, wherein

Fig. 1 is a side elevational view of the forward end of a locomotive embodying my invention;

Fig. 2 is a detail top-plan view of the structure of Fig. 1;

Fig. 3 is a diagram of the structure illustrated in Figs. 1 and 2.

Fig. 4 is a side elevational view of a modi-
fication; and

Fig. 5 is an end elevational view of the structure of Fig. 4 with the cover removed.

Fig. 6 is a diagram of the structure illustrated in Figs. 4 and 5.

In the illustrated embodiment of my invention shown in the drawings, a forward end 1 of a locomotive frame 2 constitutes a support for a boiler 3 and a smoke box 4. The smoke box 4 may have a stack 5 substantially centrally located on an upper side 6 thereof and it is also provided with an exhaust steam nozzle 7 having exhaust steam passages 8 and 9 respectively leading to valve chambers 11 and 12 of cylinders 13 and 14 positioned on the opposite sides of the locomotive frame 2, as is customary in the art.

A feed-water tank or casing 15 may be pivotally mounted by vertically positioned hingers 16 on a front edge portion 17 of the smoke box 4, whereby an imperforate rear

will 18 of the tank 15 may normally close a front open end 19 of the smoke box 4 but permitting access to the smoke box when said tank 15 is moved horizontally about the hinges 16. The imperforate wall 18 thus constitutes a front wall for the smoke box 4 and a rear wall for the tank 15. The diameter of the tank 15 is such that the walls thereof constitute substantially a continuation of the walls of the smoke box 4. The walls of the tank 15 terminate in an imperforate front plate 21 which is positioned in parallel relation to the rear wall 18.

An eductor-condenser 22 is mounted on the upper portion of the movable tank 15 so as to extend inwardly of the same. Feed water may be supplied to the condenser 22 by means of a pipe 23 leading from any suitable propelling means such as any conventional form of injector 23^a at the rear of the locomotive. The feed water entering the tank 15 through the condenser 22 may be preheated by means of exhaust steam supplied from a pipe 24, as will presently appear in greater detail.

Experience has shown that the usual boiler feed water contains large quantities of air as well as acid, and, as a result, there is a rapid deterioration of the boiler parts as well as low operating efficiency. The gas in the feed water is eliminated in the present invention by preheating the same by means of the exhaust steam from the pipe 24 to a relatively high temperature, say between 180° and 212° F. Within these temperatures, the oxygen or other gases are readily given off from the feed water upon being discharged into the tank 15, and the capacity of the tank 15 is such that the feed water is held therein in a time sufficient for the desired degasification to occur. The building up of high pressures in the tank 15 during this operation is prevented by means of a vent pipe 25 or other means offering a substantially unrestricted outlet for the liberated gases.

The undesirable chemical constituents of the feed water passing into the open tank 15 may be removed by means of any desired agent, such as limestone, which is supported in trays 26 mounted on brackets 27 extend-

ing from the imperforate rear wall 18 of said open tank 15. These trays are vertically disposed so that the discharge from the condenser 22 passes successively from one tray to the other.

5 In accordance with my invention, I mount on an upper portion 28 of the boiler 3 a closed feed-water heater 29 comprising spaced sections 31 and 32. Each of the sections is provided with spaced headers 33 and interconnecting tubes 34, whereby fluid may pass through the unit from an inlet opening 35 at one end to a discharge outlet 36 at the other end. The space between the headers 33 is adapted to receive a heating medium which may be supplied through an inlet opening 37 and discharged through an outlet opening 38. Corresponding discharge outlets 36 of the sections 31 and 32 are connected by a pipe 39. The outlet opening 35 of the section 32 may be connected by means of a pipe 41 to the boiler 3 through a check valve 42. The opening 35 of the section 31 may be connected by means of a pipe 43 to a discharge outlet 44 of a rotary pump 45. A suction end 46 of the pump 45 is connected by means of a pipe 47 to a bottom portion 48 of the open feed-water tank 15, whereby only the degasified feed water may be withdrawn therefrom.

30 The inlet openings 37 of the heater sections 31 and 32 are connected by pipes 49 and 51, respectively, to the exhaust passages 8 and 9 leading from the valve chambers 11 and 12 of the cylinders 13 and 14. The outlet openings 38 of the sections 31 and 32 are connected by pipes 52 and 53 to the common pipe 24 leading to the eductor-condenser 22.

In operation, feed water is forced by suitable means 23^a through the pipe 23 to the eductor-condenser 22 located in the open degasifying tank 15. As the feed water discharges from the eductor condenser 22, a vacuum is created, causing exhaust steam to be withdrawn from the passages 8 and 9 and to traverse passages respectively including the pipes 49 and 51, the heater sections 31 and 32, the pipes 52 and 53, the common pipe 24, and the eductor condenser 22. The steam thus supplied to the feed water causes the preheating of the same, so that as it is discharged from the condenser 22 and passed from one of the trays 26 to the other, the gases in the feed water are liberated and the undesirable chemical constituents removed. 55 The gases given off are vented by means of the pipe 25.

As above indicated, the parts are so designed that by the time the feed water reaches the suction pipe 47 leading to the pump 45, 60 complete degasification has occurred. Passing from the pump 45, the feed water is forced successively through the closed heater sections 31 and 32, where a further increase in temperature is effected by the exhaust steam from the locomotive cylinders 13 and

14 prior to its condensation in the condenser 22. Experience has indicated that the increase in temperature of the feed water at this point may amount to as much as 35°. The feed water is finally discharged from the heater sections 32 through the check valve 42 into the boiler 3.

The modification shown in Fig. 3 is distinguishable over that shown in Figs. 1 and 2 principally in the fact that the sectional feed-water heater 29 is replaced by a single unit 54 which is transversely mounted on the movable open tank 15 forward of the condenser 22. A movement of the tank 15 to open or to close the front end 19 of the fire box 4 thus results in a bodily movement of the closed feed-water unit 54 as well as the condenser 22.

A further difference is in the connection of a pipe 55 leading from a heating chamber 56 of the closed heater unit 54 directly to the exhaust nozzle 7. The heating chamber 56 is also connected by a pipe 57 to a port 58 of the condenser 22, whereby the exhaust steam passing through the heater 54 may be supplied to the condenser 22 to cause the pre-heating of the feed water, as in Figs. 1 and 2. The heater 54 may be supplied with feed water from the open tank 15 through piping 59 including the pump 45. The heater water may be discharged from the unit 54 through pipe 61 which is adapted to be connected to the boiler 3, as in the preceding system. The operation of this modification is otherwise as previously described for the system of Figs. 1 and 2.

While I have shown only two embodiments of my invention, for the purpose of describing the same and illustrating its principles of construction and operation, it is apparent that various modifications may be made therein without departing from the spirit of my invention and I desire, therefore, that only such limitations shall be imposed thereon as are indicated in the appended claims or as are demanded by the prior art.

I claim:

1. A locomotive having a boiler provided with a smoke box; an open casing forming a continuation of said smoke box pivotally mounted on the same; a condenser positioned to discharge into said casing; means for supplying feed water to said condenser and for forcing said water through said condenser into said casing; a closed feed-water heater connected to said boiler; means connecting said casing and said closed feed-water heater including a pump; steam cylinders having an exhaust passage leading therefrom; and means whereby steam from said exhaust passage may be caused to heat the feed water supplied to said closed heater and also the feed water supplied to said casing, the temperature of the water in said casing being such that the gases are liberated.

2. A locomotive having a pair of cylinders provided with exhaust passages leading therefrom; a locomotive boiler; a smoke box; a casing forming a continuation of said smoke box movably mounted relative thereto; a condenser positioned to discharge into said casing; means for forcing feed-water through said condenser; a sectional closed feed-water heater having an inlet opening, and a discharge outlet connected to said boiler; piping including a pump for propelling fluid from said casing to said inlet opening; means whereby the sections of said closed feed-water heater may be respectively heated with steam from said exhaust steam passages; and means whereby the exhaust steam after heating said closed heater may be supplied to said condenser to operate the same and to cause the heating of the feed-water discharged therefrom. 70
3. In combination, a locomotive having a boiler provided with a smoke box; an open feed-water tank positioned in advance of said smoke box; a closed feed water heater comprising a plurality of sections mounted on said boiler; means including a condenser for supplying feed water to said open tank; a pump for propelling the water from said open tank to said closed feed-water heater; piping for conducting water from said closed feed-water heater to said boiler; valve chambers provided with exhaust steam passages; and piping leading from said exhaust steam passages to said closed feed-water heater and thence to said condenser. 80
4. In combination; a locomotive boiler; a smoke box; a feed-water tank constituting a degasifying chamber movably positioned on the said smoke box; a condenser extending inwardly of the said tank and discharging therein; a closed feed-water heater; means for conducting feed water from the said tank to the said heater; means including passages in said heater for supplying the said condenser with exhaust steam and piping for conducting water from said closed feed water heater to the boiler. 90
5. In combination; a locomotive smoke box; a feed-water tank movably positioned thereon; a condenser positioned to discharge into said tank; means for supplying feed water to said condenser; a passage for exhaust steam in communication with said condenser; a closed feed-water heater having an inlet opening; means for connecting said tank to said inlet opening; and means whereby steam from said exhaust passage may be caused to first heat the feed water supplied to said closed heater and to then pass into the said tank and to heat the feed water therein, prior to said feed water being injected into said closed heater. 100
6. The combination of a locomotive boiler having an open feed-water heater; a condenser positioned to discharge into the same; means for supplying feed water to said condenser; a passage for conducting exhaust steam from the cylinders to a closed feed-water heater; said closed feed-water heater being connected to said open heater to receive water therefrom; means including passages in said closed heater for supplying said condenser with exhaust steam; and piping for connecting said closed feed water heater to the boiler. 110
7. In combination, a locomotive having an open feed-water tank; a condenser so carried by said tank as to extend inwardly thereof; a boiler, to be supplied with feed-water; means for supplying feed water to said condenser and for discharging it into said tank; a closed feed-water heater connected to said boiler; means for propelling feed water from said tank to said closed feed-water heater; and means including passages in said closed heater for supplying said condenser with exhaust steam. 120
8. A locomotive having a smoke box provided with a feed-water tank positioned to constitute a continuation of said smoke box; a condenser extending inwardly of said tank; means for supplying feed water to said condenser and for discharging it into said tank; a closed feed-water heater; means including a pump for propelling feed water from said tank to said closed feed-water heater; an exhaust steam conduit including passages through the closed feed-water heater and on to the condenser; and means whereby steam from said passages may be caused to first heat the feed water supplied to said closed heater and to then pass into the said tank and to heat the feed water therein, prior to said feed water being injected into said closed heater. 130
9. The combination in a locomotive, of a boiler; a smoke box provided with a casing forming a continuation of said smoke box so pivotally mounted thereon as to swing out of the way so as to permit access to said smoke box; a condenser positioned to discharge into said casing; means for supplying feed water to said condenser; a closed feed-water heater having an inlet opening; means including a pump for propelling water from said casing to said inlet opening; a steam passage; means for causing the steam from said passage to first heat the water in said closed feed-water heater and to then pass into said casing and heat the feed-water therein prior to said feed-water being injected into said closed heater, the size of the casing being such that for a given outlet the heated water is contained in said casing until the gases have been liberated therefrom to a desired extent; and piping for connecting said closed feed water heater to the boiler. 140
10. The combination in a locomotive, of a boiler; a smoke box; an open feed-water tank

pivottally mounted in front of said smoke box to provide ready access thereto; a condenser extending partly into said tank; means for forcing feed-water through said condenser into said tank; a sectional-feed-water heater located above said tank, the sections of which are connected in parallel for the passage of exhaust steam there-through, and in series for the passage of feed-water; means for passing exhaust steam from the cylinders to said closed heater and thence to said open heater; means for forcing feed-water from said open tank into said closed tank and piping for connecting said closed feed water heater to the boiler.
